PATENTED AUG. 16, 1904.

J. M. ROBINSON.

FLY EXCLUDING ATTACHMENT FOR SCREEN DOORS.

APPLICATION FILED JAN. 12, 1904.

NO MODEL.

Fig. 1.

UNITED STATES PATENT OFFICE.

JOSIAH MANSEL ROBINSON, OF HASTINGS, NEBRASKA.

FLY-EXCLUDING ATTACHMENT FOR SCREEN-DOORS.

SPECIFICATION forming part of Letters Patent No. 767,441, dated August 16, 1904.

Application filed January 12, 1904. Serial No. 188,706. (No model.)

To all whom it may concern:

Be it known that I, JOSIAH MANSEL ROBINSON, a citizen of the United States, residing at Hastings, in the county of Adams and 5 State of Nebraska, have invented a new and useful Fly-Excluding Attachment for Screen-Doors, of which the following is a specification.

This invention relates to attachments to 10 doors, more particularly screen-doors, for preventing flies and other insects from entering when the door is opened and also for automatically closing the door, and has for its object to improve the construction and produce a device of this character simple in 15 construction, easily applied and operated, and which may be applied with equal facility to double doors and to doors swinging in both directions through the doorway-opening.

With these and other objects in view, 20 which will appear as the nature of the invention is better understood, the same consists in certain novel features of construction, as hereinafter fully described and claimed.

In the accompanying drawings, forming a 25 part of this specification, and in which corresponding parts are denoted by like designating characters, is illustrated the preferred form of the embodiment of the invention 30 capable of carrying the same into practical operation, it being understood that the invention is not necessarily limited thereto, as various changes in the shape, proportions, and general assemblage of the parts may be 35 resorted to without departing from the principle of the invention or sacrificing any of its advantages, and the right is therefore reserved of making all the changes and modifications which fairly fall within the scope of the 40 invention and the claims made therefor.

In the drawings, Figure 1 represents the upper portion of a double screen-door with the improvement applied. Fig. 2 is a plan view of portions of the contiguous or meeting edges of the doors with the corresponding 45 portions of the improved device attached. Fig. 3 is an edge view of the upper portion

of one of the doors with the corresponding portion of the improved device attached.

The improved device may be attached to 50 any form of swinging door in any locality where flies, mosquitoes, or other similar insects abound and which it is desirable to exclude, but is more particularly applicable to screen-doors and for the purpose of illustration is shown thus applied, the frame and casing 10 and doors 11 being of the usual construction.

The device is shown applied to double doors 55 for swinging in both directions through the doorway-opening to show the scope of the invention; but it will be understood that the invention is equally applicable to single doors and to doors swinging in one direction only.

The improved device consists of spring-controlled rollers 12, mounted for vertical rotation adjacent to the free edges of the doors, as by lower brackets 13 and upper brackets 14. The spring-controlled rollers will preferably be ordinary spring curtain-rollers, 70 which fully meet the required conditions, and to support them detachably in position the brackets 14 are formed with open slots, in which the flat pivots 16 of the rollers are seated to prevent rotation and retained in 75 place when in operation by swinging stop-latches 17, having recesses to embrace the pivots. By this simple means the rollers are held in the same manner as the rollers are held upon ordinary window casings or frames and 80 readily detachable, as required, when the springs are to be adjusted. The rollers 12 are armed with radiating brush members 18, which may be of light muslin or other similar fabric cut into strips and preferably applied 85 in scroll form, winding around the rollers longitudinally.

Attached by one end to the roller 12, preferably near its upper end, is a cord 19, wound about the roller, as a drum, and with the other 90 end connected to a bracket 20 on the door frame or casing 10. The cord will be wound upon the drum reversely to the spring within the roller 12, so that the tension of the spring

will be exerted to maintain the cord tightly wound up, and thus hold the door yieldably closed. When the door is opened, the cord in unwinding from the roller will rapidly rotate it in one direction and cause the brush member 18 to be rapidly rotated and drive all flies and other insects away from the door, and when the door is released the spring-roller in its return movement will rapidly rotate the brush in the opposite direction and at the same time automatically close the door by rewinding the cord on the roller, as will be obvious. The brush member is thus rapidly rotated both in opening and closing the door and all the flies and other insects effectually driven away from the doorway.

A guard member 21, preferably of wire, is attached to the door to serve as a keeper to guide the cord in winding upon and unwinding from the roller, and embedded in the door opposite the guard member 21 is a guide-roller 22, over which the cord runs while the door is opening and closing to prevent the cord being worn over the edge of the door.

The bracket 14 is provided with a vertical web 23, having a bearing for the pivot of a roller 25, by which one end of the roller is rotatively mounted, the other end of the roller being similarly mounted by a pivot in a bracket 27 on the door near its hinged edge and also near its upper edge. The roller 25 is thus horizontally mounted for rotation near the upper edge of the door and is armed with a brush member 28, similar to the brush member 18 on the spring-roller 12. The adjacent ends of the rollers 12 and 25 are provided with interengaging bevel-gears 29 30, whereby the rotary motion of the roller 12 is communicated to the roller 25. By this arrangement it will be noted when the door is opened and closed the rollers 12 25, with their attached brush members, will be rapidly rotated near the upper portion of the door, where the flies accumulate, and effectually drive them away and prevent them passing through the doorway-opening.

When applied to double doors, the central hanger or bracket 20 will be attached to the frame opposite the juncture or meeting-point of the doors, to which the ends of the cords 19 will be connected, so that the doors may be independently operated. The doors will be cut away slightly to permit them to pass the hanger 20 in opening.

It will be noted that the presence of the brush-rollers, brackets, and other attachments does not interfere with the movement of the door in any manner and they may be applied to double-acting doors or those swinging entirely through the doorways, as will be obvious.

Having thus described the invention, what is claimed is—

1. The combination with a door, of upright and transverse fly-brushes mounted thereon and connected for simultaneous rotation, and means connected to one of the brushes and to the door-frame for rotating said brush during the opening of the door.

2. The combination with a door of angularly-related rotatable fly-brushes carried thereby, one of the brushes being spring-actuated, meshed gears carried by the brushes, and means connected to the spring-actuated brush and to the door-frame to rotate said brush during the opening of the door.

3. The combination with a swinging door, of a rotatable fly-brush carried thereby, a cord wound upon the fly-brush and extending across the free edge of the door into connection with the door-frame, an antifriction-roller carried by the free edge of the door and receiving the cord, and a cord-guide carried by the door and located between the roller and the brush.

4. The combination with a door, of a spring-controlled roller vertically mounted for rotation adjacent to the free edge of the door, and provided with brush members, said roller having a bevel-gear upon its upper end, a substantially horizontal roller mounted for rotation upon said door at its upper end and provided with brush members, said roller having a bevel-gear operatively engaging the gear upon said spring-roller, and a cord wound upon said spring-roller and connected to the door-casing by its free end, whereby the opening and closing of the door will cause the rapid simultaneous rotation of said brush-supporting rollers adjacent to the side and upper end of the door and doorway-opening.

5. The combination with a door, of a bracket attached thereto adjacent to the upper outer corner of its free edge and formed with a horizontal web and a vertical web, said vertical web having an aperture forming a roller-bearing and said horizontal web having an open slot, a swinging latch to close the slot, a spring-controlled roller having brush members and with one of its journals held from rotating in said open slot and retained therein by said latch, a roller having brush members and mounted for rotation in the bearing in said vertical web, said rollers having interengaging gear-wheels on their contiguous ends, and a cord wound around said spring-controlled roller and connected by its free end to the door frame or casing.

6. The combination of a door-frame having two doors mounted to swing therein with their free edges contiguous, spring-controlled upright rollers having brush members and mounted for rotation adjacent to the free

contiguous edges of said doors and provided with bevel - gears at the upper ends, substantially horizontal rollers mounted for rotation adjacent to the upper edges of said doors and having brush members, said horizontal rollers having bevel - gears engaging the bevel - gears on said spring - controlled rollers, a bracket depending from the door frame or casing in alinement with the junction of said doors, and cords connected to

said depending bracket and wound around the respective spring-controlled rollers.

In testimony that I claim the foregoing as my own I have hereto affixed my signature in the presence of two witnesses.

JOSIAH MANSEL ROBINSON.
